UNITED STATES PATENT OFFICE.

OTTO R. SELL, OF COLORADO SPRINGS, COLORADO.

HEAD-LAMP CONTROL.

1,201,880.

Specification of Letters Patent. Patented Oct. 17, 1916.

Application filed January 26, 1916. Serial No. 74,430.

To all whom it may concern:

Be it known that I, OTTO R. SELL, a citizen of the United States, residing at Colorado Springs, in the county of El Paso and State of Colorado, have invented new and useful Improvements in Head-Lamp Controls, of which the following is a specification.

This invention relates to headlamp controls of that character in which, in order to comply with the traffic regulations within certain boundaries or city limits, it is necessary to change the direction in which the rays of light are projected from the lamp so that they will not blind and otherwise confuse pedestrians and the drivers of other vehicles.

The invention relates particularly to headlamps employing incandescent light producing devices and has special reference to the holding and shifting means for such lamps or sources of light by means of which the focused rays of light may be controlled from the operator's station in the vehicle upon which the invention is employed.

By means of the invention hereinafter particularly described, the rays of light may be thrown at various angles with respect to a horizontal plane so as to be projected straight ahead for practically illuminating the road way when beyond the limits and diverted or thrown at a downward angle on the roadway so as to illuminate only a small area or zone directly in front of the machine, the desired result being obtained by a change in the position of the light producing element in relation to the reflecting surface of the headlamp.

With the above and other objects in view, the invention consists in the novel construction, combination and arrangement of parts, as herein described, illustrated and claimed.

In the accompanying drawings:—Figure 1 is a diametrical section through the bearing and journal for the lamp support, showing also the tensioning means. Fig. 2 is a vertical section through a portion of the lamp case, showing the reflector, the light producing element and the means for shifting the position thereof, under one embodiment of the invention. Fig. 3 is a section taken on the same line as Fig. 2 showing a modified and somewhat simpler arrangement of lamp shifting mechanism.

Referring to the drawings, A designates what will be hereinafter termed as the lamp

support. The main body of this support is cylindrical in shape or round in cross section and under the arrangement shown in Fig. 2, at one end of the body of the support, the latter is provided with an arm A' extending substantially at right angles thereto and terminating in an obliquely disposed angular end portion a' which is bored to form an eye or receptacle for a lamp socket n which is shown as fastened in place in relation to the part a' by means of a screw b'.

s designates the light producing element shown in the form of an ordinary incandescent electric lamp fitted into the end of the socket member n.

m designates the current wires which lead through an opening o in the lamp socket n to the lamp s.

The reflector r is provided with an orifice p through which the member n extends in order to allow for shifting the lamp s by mechanism to be hereinafter described.

The lamp support A passes through a diametrical or axial bore f in a spherical journal member b, contained within a bearing a which is cupped or internally concaved to conform to the outer surface of the journal b as clearly shown in the drawings. The bearing member a is also provided with a flange or flanges f' having openings to receive fasteners g' by means of which the bearing a is secured to the casing k of the lamp containing the reflector r. One or more of said screws may be employed as shown in Figs. 2 and 3 to also fasten to the flange or flanges f' a reflector supporting arm r' to which the reflector r is fixedly secured in any convenient way.

Threaded pivots i are inserted through the bearing a at diametrically opposite points and are threaded into and through the journal member b as shown at h'. The inner extremities of the pivots i which are shown in the form of screws, are adapted to engage the support A and prevent relative movement in any direction between said lamp support and the spherical journal member b. At the same time the threaded pivots or screws i allow the lamp support A to be adjusted toward and away from the reflector so that the lamp s may be correspondingly adjusted together with the socket n to allow for the full amplitude of movement of the lamp.

The bearing a is externally threaded as shown at y to receive a presser cap d which

is therefore adjustable in relation to the bearing a . A friction shoe c is inserted in one end of the bearing a and is formed with a concaved working face as shown which 5 conforms to the outer surface of the spherical journal member B . Between the friction shoe c and the cap d , a resilient and expansible member e is interposed, the same being preferably in the form of a ring of 10 rubber or the like, said resilient member serving to hold the shoe c in contact with the journal member b with a pressure which will prevent the journal b from turning too freely. The friction shoe c is provided with 15 an outwardly flaring opening g and the cap d is also provided with an outwardly flaring opening h both of which flaring openings correspond with the central opening of the resilient member e which is also flared. At 20 the opposite side, the bearing a is provided with the flared opening j . All of the openings just referred to provide for the necessary amplitude of oscillatory movement of 25 the lamp support A on the pivots i as a center thus enabling the lamp support A and the lamp s to be moved to the two extreme limits of movement indicated by full and dotted lines in Figs. 2 and 3.

The means for operating the lamp support 30 is shown for convenience as embodying a rod u pivotally connected at t to one end of the lamp support and pivotally connected at its other end to the free extremity of an arm v on a rock shaft z under the control of the operator in his seat in the machine.

Under the arrangement illustrated in Fig. 3 of the drawings, the parts A' , a' and b' of Fig. 2 are dispensed with and the lamp socket n is formed directly on one end of the lamp support A and in fact forms a continuation thereof. The orifice p of the reflector r is located at a relatively higher elevation so that the socket n may extend 45 directly therethrough and have the lamp s detachably attached thereto, the orifice p being so designed and located that the lamp s may be shifted to either of the two limits of its movement as indicated by the full and dotted lines in said Fig. 3.

x designates smooth openings in the bearing a through which the pivots i are inserted, said pivots being adapted to turn freely in the bearing openings x .

50 The presser cap d is preferably roughened or knurled as shown at x' . By adjusting the presser cap d in relation to the bearing a , the resilient member e may be caused to bear with any desired yielding pressure against the friction shoe c , the latter thereby acting with greater or less friction on the journal member b to resist the turning movement of the latter. Additionally, the resilient member e when compressed between the cap d 55 and the shoe c will slightly bulge at its in-

ner edge so as to form a cushion against which the lamp support A will strike and bear when the lamp s assumes the dotted line position in Figs. 2 and 3. This reduces the liability of the breaking of the lamp by vibrations of too great amplitude. 70

In whatever position the lamp s is adjusted, it is securely retained by the operation of the friction shoe c in conjunction with the bearing a , the concaved faces of both of which parts lie in direct contact with the outer surface of the spherical journal member b . When the lamp is in the central position illustrated by full lines in Figs. 2 and 3, the rays of light are thrown directly ahead for the purpose of illuminating the road way to a considerable distance in front of the machine. When, however, the lamp is shifted to the position indicated by dotted lines in the drawings, the rays of light instead of being directed straight ahead, are deflected and directed downwardly at an angle so as to illuminate only a relatively small zone or area in advance of the machine. 80

Having thus described my invention, I claim:-

1. The combination with a concaved reflector having an orifice in the body thereof, of a lamp support, a lamp carried thereby and movable upwardly and downwardly within the concavity of the reflector, a spherical journal member formed with an axial bore through which a portion of said lamp support passes, a bearing for said journal member, threaded pivots inserted through said bearing and journal member coincident with the axis on which the journal member turns, a friction shoe movable within said bearing having a concaved working face in contact with said spherical journal member, tensioning means for said friction shoe, and manually controlled means connected with said lamp support for shifting said lamp. 95

2. The combination with a concaved reflector having an orifice in the body thereof, of a lamp support, a lamp carried thereby and movable upwardly and downwardly within the concavity of the reflector, a spherical journal member formed with an axial bore through which a portion of said lamp support passes, a bearing for said journal member, threaded pivots inserted through said bearing and journal member coincident with the axis on which the journal member turns, said pivots engaging the lamp support at their inner ends, a friction shoe movable within said bearing having a concaved working face in contact with said spherical journal member, tensioning means for said friction shoe, and manually controlled means connected with said lamp support for shifting said lamp. 115

3. The combination with a concaved re- 120

5 reflector having an orifice in the body thereof, of a lamp support, a lamp carried thereby and movable upwardly and downwardly within the concavity of the reflector, a spherical journal member formed with an axial bore through which a portion of said lamp support passes, a bearing for said journal member, a friction shoe movable within said bearing having a concaved working face in contact with said spherical journal member, 10 tensioning means for said friction shoe embodying a presser cap adjustable in relation to said bearing, and manually controlled means connected with said lamp support for shifting said lamp.

15 4: The combination with a concaved reflector having an orifice in the body thereof, of a lamp support, a lamp carried thereby and movable upwardly and downwardly within the concavity of the reflector, a spherical journal member formed with an axial bore through which a portion of said lamp support passes, a bearing for said journal member, a friction shoe movable within said bearing having a concaved working face in contact with said spherical journal member, tensioning means for said friction shoe embodying a presser cap adjustable in relation to said bearing, and manually controlled means connected with said lamp support for shifting said lamp.

20 25 cal journal member formed with an axial bore through which a portion of said lamp support passes, a bearing for said journal member, a friction shoe movable within said bearing having a concaved working face in contact with said spherical journal member, tensioning means for said friction shoe embodying a presser cap adjustable in relation to said bearing, a resilient and expandible shoe-thrusting member between 30 said friction shoe and cap, and manually controlled means connected with said lamp support for shifting said lamp.

25 In testimony whereof I affix my signature in presence of two witnesses.
